US00D537062S

(12) **United States Design Patent** (10) **Patent No.:** **US D537,062 S**
(45) **Date of Patent:** **** Feb. 20, 2007**

(54) **PORTABLE PHONE**

(75) Inventors: **Eun-Young Kim**, Seoul (KR);
Jong-Seong Lee, Seoul (KR); **Yang-Jic Lee**, Seoul (KR)

(73) Assignee: **Samsung Electronics Co., Ltd.**,
Suwon-Si (KR)

(**) Term: **14 Years**

(21) Appl. No.: **29/236,926**

(22) Filed: **Aug. 25, 2005**

(30) **Foreign Application Priority Data**

Feb. 25, 2005 (KR) 30-2005-0006300

(51) **LOC (8) Cl.** **14-03**

(52) **U.S. Cl.** **D14/138**

(58) **Field of Classification Search** D14/137,
D14/138, 147-148, 247-248, 144, 496, 156,
D14/341-347, 191, 192; 379/433.01-433.13;
455/575.4, 566, 575.1, 556.1, 556.2, 90.3,
455/41.2; D21/329, 331, 333; D16/208
